UNITED STATES PATENT OFFICE.

JOSIAH E. REID AND CHARLES L. NEIN, OF NEW YORK, N. Y., ASSIGNORS TO INTERNATIONAL MOTOR COMPANY, OF NEW YORK, N. Y., A CORPORATION OF DELAWARE.

GATE FOR DUMPING BODIES.

Application filed September 15, 1923. Serial No. 662,962.

To all whom it may concern:

Be it known that we, JOSIAH E. REID and CHARLES L. NEIN, citizens of the United States, and residents, respectively, of the borough of Manhattan and of the borough of Queens of the city of New York, in the State of New York, pray that Letters Patent of the United States may be granted to us for new and useful Improvements in Gates for Dumping Bodies, of which the following is a specification, reference being had to the accompanying drawings, forming a part hereof.

This invention relates to gates for dumping bodies and particularly the locking mechanism therefor and is designed primarily with reference to its use as a partition for such a body as distinguished from a tail gate although as the description proceeds it will be evident that the partition might be so employed. The principal object of the invention is to provide a construction which is characterized by fewness of parts, simplicity of construction and arrangement, ease in assembling and disassembling, and certainty of operation through the positive nature of the latching elements. Still another object of the invention is to provide latching devices for such a gate which may be readily operated by hand and normally free from the action of unbalanced forces, particularly at the instant of release, such as in known constructions make the release of the gates under pressure a somewhat difficult and hazardous operation. Still a further object of the invention is to provide such a latch as will be automatically engageable with the gate when the body is lowered to position on the chassis. A further object of the invention is to construct the parts so that they shall be operable positively under all conditions and free from springs.

These and other objects of the invention will be described with greater particularity hereinafter in connection with the embodiment illustrated in the accompanying drawings, wherein:

Figure 1 is a view in rear elevation of a gate constructed and mounted in accordance with the present invention and having associated therewith the improved locking means.

Figure 2 is a view of a fragment of the gate shown in Figure 1 but shown on a somewhat larger scale.

Figure 3 is a view in side elevation thereof and showing particularly the locking relation between the swinging gravity latch and the gate.

As pointed out hereinbefore, the improvements are not limited to the particular location or function of the gate provided since it is evident that it might be so placed on a body as to serve as a tail gate although the disclosure herein is that of a gate designed for use as a partition in a dumping body in which it is believed it will find its greatest usefulness. The gate *a* itself may be of any suitable construction re-enforced as may be necessary to withstand pressure imposed thereon by the material at one side or the other. It carries at its upper edge or opposite sides laterally extending trunnions *a'*, *a''*, which may be inserted removably within brackets *b* secured to the vehicle body, a part of which is indicated at *c*, at opposite sides thereof and slotted as at *b'* to permit the free introduction and removal of the pin when the gate is attached or detached all in a manner which will be evident. The pins *a'*, *a''*, permit the gate to hang normally in a substantially vertical position as indicated in Figure 3 under the influence of gravity and to swing rearwardly when released to permit discharge of the material restrained thereby when the body is tilted for dumping. The construction thus far described is simple, rugged and accessible and permits the gate to be readily mounted in the body or removed therefrom as required. However, the most important feature of the invention resides in the means for locking the gate in position against movement and for unlocking it readily when the contents of the body are to be discharged. At one side of the body *c* as indicated clearly in Figure 2 there is mounted pivotally on a pin *d* a swinging lock bar *e* which is bent to throw its lower end *e'* at one side of the center of the pin *d* when the bar is in normal position for a purpose which will appear more clearly hereinafter. The lower end *e'* of the bar may constitute a handle and be weighted to increase the gravity action described while facilitating manual swinging of the bar about the pin *d* against the action of gravity when the latch is to be tripped. The upper edge of the bar is formed with a beveled surface *e''* while in proximity thereto and along one side edge is formed an open slot

e^3 for engagement with a locking pin f secured to the gate a and offset with respect to the trunnion a' but preferably in substantially the same horizontal plane therewith. 5 From the construction described it will be clear, especially with reference to Figure 3, that when the dumping body is in normal position on the chassis the gate a hangs in a substantially vertical position on the 10 trunnions a' , a^2 , and is held against swinging movement positively by engagement of the lock bar e with the locking pin f . A positive engagement of the pin f by the upper end of the lock bar is maintained automatically by the action of 15 gravity on the lower end of the lock bar, which is preferably augmented by provision of the weight e' . This condition is maintained automatically even when the 20 body is tilted for dumping and the material is held against discharge by the face of the gate a until the latch bar is swung about the pivot d to release the pin f from the slot e^3 . Such a manual operation must be effected against the action of gravity on the lock bar e . However, by disposing the pin f in a plane with the trunnions a' , a^2 , which is substantially at right angles to the plane of the gate a it will be evident that the 25 forces impressed on the locking bar by the pin f are in a plane substantially parallel to the plane of the gate a , that is, in a plane substantially at right angles to the edge of the slot e^3 so that when the locking bar is 30 swung out of engagement with the pin f the latter is free to swing about the trunnions a' , a^2 , without impressing on the locking bar any unbalanced forces which might serve to snap it quickly around its supporting pin 35 d or otherwise make it difficult or hazardous for the final disengagement to be brought about. After the material has forced its way past the swinging gate a during the dumping operation the body will be lowered 40 to the chassis for subsequent refilling. As the body is lowered the gate a under the influence of gravity swings towards a substantially vertical position about the trunnions a' , a^2 . This movement will eventually 45 bring the pin f down onto the beveled nose e^2 at the upper end of the locking bar and the bar itself will be swung about its pivot d against the action of gravity impressed 50 on the lower end thereof until the pin f is 55 in alignment with the slot e^3 when the bar will snap into locking engagement with the

pin and be maintained in this position by gravity as previously described.

From the description given it will be appreciated that the entire construction is simple, accessible, rugged, positive in action and free from springs. Changes in matters of design and arrangement of parts may be made without departing from the spirit of the invention so long as the principle described is practiced by means equivalent to those recited in the appended claims.

What we claim is:

1. In a dumping body a transverse gate therefor, trunnions mounted on the gate and extending laterally therefrom, means carried on the body for supporting the trunnions with capacity for oscillation, a locking pin mounted on the gate in spaced relationship to said trunnions and in a plane therewith at substantially right angles to the plane of the gate and a lock bar co-operating with said locking pin to restrain the gate. 75

2. In a dumping body a transverse gate therefor, trunnions mounted on the gate and extending laterally therefrom, means carried on the body for supporting the trunnions with capacity for oscillation, a locking pin mounted on the gate in spaced relationship to said trunnions and in a plane therewith at substantially right angles to the plane of the gate, a lock bar co-operating with said locking pin to restrain the gate, and gravity means carried with said locking bar to maintain it normally in locking engagement with said pin. 80

3. In a dumping body a transverse gate therefor, trunnions mounted on the gate and extending laterally therefrom, means carried on the body for supporting the trunnions with capacity for oscillation, a locking pin mounted on the gate in spaced relationship to said trunnions and in a plane therewith at substantially right angles to the plane of the gate, a lock bar co-operating with said locking pin to restrain the gate, and gravity means carried with said locking bar to maintain it normally in locking engagement with said pin, said locking bar having its upper edge beveled to facilitate automatic engagement of the bar with the locking pin when the gate swings into its substantially vertical position after dumping. 100

This specification signed this 12 day of September A. D. 1923.

JOSIAH E. REID.
CHARLES L. NEIN.
